UNITED STATES PATENT OFFICE.

JOHN U. BARR, OF NEW YORK, N. Y., ASSIGNOR OF TWO-THIRDS TO FREDERICK G. EBSARY,
OF HUGUENOT PARK, AND LOUIS STRUEVER, OF NEW YORK, N. Y.

CAN.

No. 912,526.

Specification of Letters Patent.

Patented Feb. 16, 1909.

Application filed August 20, 1908. Serial No. 449,463.

To all whom it may concern:

Be it known that I, JOHN U. BARR, a citizen of the United States, residing at New York city, in the borough of Manhattan, county and State of New York, have invented a certain new and useful Improved Can, of which the following is a clear, full, and exact description.

The object of this invention is to provide a can which may be worn beneath the coat, and affixed to a garment of the wearer, and particularly adapted for the carrying of beer or other liquids, so that one who prefers draft beer can overcome the popular prejudice against "rushing the can" and will be able to get the draft beer and transport it to one's home without giving rise to comment.

A further object is to so construct the can that it may be hung either in the arm hole of the coat or of the vest without changing the position of the can with relation to the body of the person using the same.

In order to cause the can to fit closely between the body of the wearer and his coat or other outer garment, I form the can with a concave and convex side, and relatively narrow. I provide a bail having a hook which will hook over the arm hole of the vest or of the coat sleeve on the inside of the same. I prefer to have the hook a double hook so that it can be hooked either on the arm hole or in the sleeve.

The scope of my invention will be pointed out in the claim.

In the accompanying drawings, Figure 1 is a front elevation showing the concave face of the can, the can being partly broken away at its upper portion. Fig. 2 is a plan view of Fig. 1. Fig. 3 is a perspective view of the hook of Figs. 1 and 2. Fig. 4 is a perspective view of the single hook. Fig. 5 is a perspective view of a modified form of double hook.

As shown in Fig. 1, the can body proper 1 is the form with an overturned edge or reinforcing rod 7 at its upper open edge. It has concave and convex sides, preferably with rounded ends. The can is preferably open across its entire top for ready cleaning, and to aid the drawer of draft beer to foam the same, as is the habit and custom in the trade. A cover 2 with a dependent flange to fit the interior of the can may be provided, and it may have a loop 6 as is customary in most cases. Staple or other

securing means may be fastened at opposite ends of the long diameter of the can, and a bail 3 preferably of wire is hung in the staples.

In the preferred form of my invention shown in Figs. 1 to 3 inclusive, the wire 3 which forms the bail, is twisted together a little over the center of the same, and the loop above the twist bent over as shown in Fig. 3 to form a hook 5 on both sides of the bail. It will be obvious that the hook adjacent to the concave side of the can will nicely fit into the arm hole of the vest of the wearer, or the opposite hook may fit into the arm hole of the coat, or both hooks may be brought into play, one upon the vest and one upon the coat. I prefer that the bail be so located in relation to the can as shown in Fig. 2, that the hook will come substantially in line with the concave side of the can at the center thereof, so that the can will tend to hang with its bottom and top horizontal when suspended from the bail.

In Fig. 4 I have shown a single hook 8 formed from the center loop of the bail 9, in other respects the can supplied with this hook will be identical with the can heretofore described.

In Fig. 5 I have shown the bail 12 as provided with a freely rotatable sleeve 11, on its central part, which is formed horizontal and straight. The sleeve 11 carries double hooks 10, so that the lower hook 10 may be swung over to the top to engage with the arm hole of the coat or the device may be used as shown so that the upper hook may be engaged with the arm hole of a vest.

I claim as my invention:

An article of the character described, comprising a can having concave and convex sides, and being relatively narrow across its short diameter, a bail for said can, said bail being partially twisted intermediate its ends, and having a portion adjacent the twisted portion formed to provide a pair of opposed looped hooks, said hooks being disposed to one side of the twisted bail portion and adapted to be engaged by the coat-sleeve and vest of the carrier.

Signed at New York city this 19th day of August 1908.

JOHN U. BARR.
